COUPLER SPREADER

Arthur E. Small, Chicago, Ill., assignor, by mesne assignments, to The Symington Company, New York, N. Y., a corporation of Maryland

Application March 1, 1928. Serial No. 258,257

8 Claims. (Cl. 213—69)

The device relates to attachments of a car coupler to the draft gear or shock absorber of a railway car and comprises a coupler having a shank consisting of two pieces pivoted and interlocked together to accomplish certain desired objects. The device might also be described as a coupler having a spreader hinged and interlocked therewith.

The object of the invention is to increase the life of the coupler by decreasing the wear and mashing of the rear end of the shank where it engages the draft gear follower or casing.

Another object of the invention is to increase the life of the coupler by increasing the bearing area between the draft key and the coupler.

Another object of the invention is to provide means so that the car coupler will have a surface contact with the draft gear casing (or follower) in any lateral position it may assume in service.

Another object of the invention is to provide means so that the car coupler will have a surface contact with the front draft key in any lateral position it may assume in service.

Another object of the invention is to provide a spreader or swivel block connected to the coupler shank or stem so as to provide arcuate buffering (compression) and pulling (tension) surfaces therebetween.

Another object is to provide an arrangement for locking the spreader to the coupler and forming them so they can be assembled only by certain movements, which movements they cannot make while in assembled position with associated parts of the car.

Another object is to attach the spreader to the coupler without any hinge or fulcrum pin, and in fact, without any split key, cotter, nut or similar securing means.

Another object is to provide a spreader which prevents the portions of a bifurcated coupler shank from spreading or coming together when the coupler is under compression or tension.

Another object is to provide a spreader which is reversible and cannot be improperly applied to the coupler.

In the drawings:

Fig. 1 shows the coupler, spreader, draft gear and associated parts of the car when the draft gear is in compressed position and the coupler head is swung laterally.

Fig. 2 is similar to Fig. 1 but shows the coupler pulled outwardly.

Fig. 3 shows the relation of the coupler shank and the spreader in normal position.

Fig. 4 is a side elevation of Fig. 3.

Fig. 5 shows the spreader partially assembled with the coupler shank.

Fig. 6 is a perspective view of the rear end of the coupler shank.

Fig. 7 is a perspective view of the spreader.

Fig. 8 shows the relation of the coupler shank and the spreader of a modified form of the invention in normal position.

Fig. 9 is a side elevation of Fig. 8.

Fig. 10 shows the modified spreader partially assembled with the coupler shank.

Fig. 11 is a perspective view of the rear end of the modified coupler shank.

Fig. 12 is a perspective view of the modified spreader.

The usual parts of the car are shown, such as coupler head 1; coupler shank or stem 2; draft gear or cushioning mechanism 3; draft sills 4; front draft key 5; rear draft key 6; yoke 7; striking casting 8 and rear draft gear stop 9.

In the ordinary construction the buff on the coupler is transmitted to the front element of the cushioning mechanism or draft gear casing 10 (or follower) by the coupler shank 2 and the pulling force on the coupler is transmitted to the draft gear through the draft keys and yoke.

In the form illustrated the coupler is provided with oppositely projecting vertically disposed pivots or pivotal means 20, each having an arcuate pulling surface toward the front of the coupler and an arcuate buffering surface toward the rear of the coupler, both of said surfaces being coaxial with a point 23 positioned between them, and the rear end of the coupler 24 is correspondingly curved flush with the arcuate buffering surface.

The spreader has spaced apart horizontal flanges 30—31 connected by a main wall 32 and has a flat bearing surface 33 for engagement with the draft gear casing or follower. Each flange is provided with a vertically disposed arcuate rib 34. Arcuate faces 37 are provided on the front of the spreader wall which slidably engage the arcuate rear end 24—22 (or ends) of the coupler. This bearing surface 33 is made as long as is permitted by the space between the arms of the yoke (see Fig. 3) so as to reduce the wear on the key and eliminate the elongation of the keyway.

The coupler now in general use is provided with a slot to accommodate the forward draft key 5 and the size and location of this slot and key are prescribed by the A. R. A., therefore, for interchangeability I prefer to comply with

these standards, but in my construction this keyway slot or perforation 60 is located in the spreader but has the same relative position to the coupler head shank, etc., as prescribed by the 5 A. R. A., and is located entirely in the intermediate flange, spacer or lateral extension 61 of the spreader (see Fig. 7) and the rear end of the shank of the coupler is bifurcated, or formed with rearwardly extending flanges, (54—55) intercalated with the swivel block flanges, and 10 accommodating the spacer or intermediate flange 61 therebetween (see Fig. 6.) The perforation 60 is a keyway for the key 5 which operatively connects the coupler to the yoke 7. 15 The portions 58—59 of the spacer 61 on opposite sides of the slot or perforation 60 are connected by a wall or end 62 to increase the bearing area, under buff, between the coupler and the spreader. (This wall also holds these portions 58—59 from warping when the casting 20 is cooling after being removed from the mould.) Were it not for the arcuate portion 62 of the spreader the crotch or curved portion 63 of the coupler shank would strike the key 5 upon the 25 sudden rearward movement of the coupler from position shown in Fig. 2 to position shown in Fig. 1 which would cause friction between the coupler and key, thus retarding the free swing movement of the coupler in service. And further, the enclosed ends of the spacer in the spreader keeps the spreader at right angles to the key and after the key is inserted, the spreader is prevented from turning. The forward end 30 or wall 62 of the spacer 61 and the forward end of the coupler slot 63 are concentrically curved. These surfaces are preferably concentric with the curved buffering surfaces 21 on the pivots 20 and rear end 24 of the coupler. The spacer 61 projects into the slot of the coupler so that when 35 the coupler is under compression this spacer prevents the spaced apart portions 54—55 of the bifurcated coupler from coming together, and furthermore, the flanges 30—31 of the spreader prevent the portions of the split coupler from 40 spreading apart.

The spreader is assembled with the coupler by inserting the coupler shank in the spreader until the axis of the coaxial arcuate or cylindrical surfaces of the pivots coincides with the 45 axis of the arcuate surfaces on the spreader and then rotating or swinging the spreader substantially ninety degrees. When the parts are assembled (see Fig. 3) and the yoke 7 and key 5 are in place it is impossible for the spreader 50 to become disengaged from the coupler or even to become cocked or assume a binding position.

In the operation of my device the compression or buff exerted on the coupler is transmitted by the arcuate buffering surface 22 on the pivots and 55 the arcuate buffering surfaces 24 on the rear end of the coupler to the arcuate surfaces 37 on the wall of the spreader and thence to the draft gear casing, 10.

The pulling force exerted on the coupler is 60 transmitted to the spreader through the pulling surface on the pivots and thence to the draft gear through the front draft key 5 and the yoke.

In my arrangement, therefore, there is a surface contact (in contrast with a line contact) 65 between the spreader and draft gear casing or follower and between the coupler and spreader in any lateral swung position the coupler may assume in service when the coupler is under 70 either compression or tension, and, furthermore,

there is always a surface contact between the coupler and front draft key when the coupler is pulling the car no matter what lateral position it may be in.

This interlocking arrangement eliminates the necessity of a hinge pin which is very undesirable because it is broken in service and frequently falls out of position, thus causing the device to become inoperative and resulting in serious damage to the car. I have also eliminated the use of any nut or split key or similar retaining means for any part of my device. Experience has shown that such devices are frequently inadvertently or otherwise omitted by the workmen and are sometimes loosely applied so that the jolting of the car in service jars them entirely out of place.

The spreader is made symmetrical about its middle horizontal plane so that it may be applied either way; or in other words, is reversible and furthermore is foolproof in that it cannot be improperly applied.

In the modification shown in Figs. 8 to 12 inclusive the spreader having a slotted keyway 70 formed therein is provided with oppositely 100 projecting vertically disposed pivots 71 each having an arcuate buffering surface 72 toward the front of the spreader and an arcuate pulling surface 73 toward the rear of the spreader, both of said surfaces being coaxial with a line 74 positioned between them. The spreader is also provided with an arcuate buffering surface 75 coaxial with the same line 74.

The rear end of the coupler is provided with spaced apart horizontal flanges 77—78 each of 110 which is provided with a vertically disposed arcuate rib 79 coaxial with and slidably engaging the groove between the arcuate pulling and buffering surfaces 73—75 on the spreader.

The spreader is assembled in a similar manner to that described for the preferred form and the operation of the modified form of my invention in service is practically the same as that described for the preferred form; in fact, the modified form shows the coupler shank formed 120 to embrace the spreader instead of the spreader embracing the coupler shank, as in the first form. The pivots 71 are shown on the spreader instead of on the rear end of the coupler (20) and the embracing flanges 77—78 on the coupler 125 instead of on the spreader (30—31).

I have used the term draft gear casing to indicate the box or housing which usually encases the shock absorbing mechanism. The projection 39 maintains the proper relation between the 130 coupler and draft gear.

The accompanying drawings illustrate the preferred form of the invention, though it is to be understood that the invention is not limited to the exact details of construction shown and described, as it is obvious that various modifications thereof within the scope of the claims will occur to persons skilled in the art.

In applications for patents Serial No. 251,329 and No. 251,330, filed February 2, 1928, I have 140 disclosed and claimed certain interlocking features between a coupler and a spreader which are disclosed but not claimed in this application.

Although I have disclosed preferred embodiments of my invention, it will be understood 145 that modifications may be made within the spirit and scope of the appended claims.

I claim:

1. In a railway car, a car coupler having a slot forming spaced apart portions, each pro-

- vided with a vertically disposed integral pivot having an arcuate buffing surface and an arcuate pulling surface co-axial therewith, and a spreader having arcuate buffing and pulling surfaces 5 faces slidably engaging the buffing and pulling surfaces respectively on the coupler provided with a spacer positioned within said slot having a horizontally disposed perforation therein. 2. In a railway car, a car coupler having spaced apart portions forming a slot, each portion provided with a vertically disposed integral pivot having an arcuate buffing surface and an arcuate pulling surface co-axial therewith, with the end of each portion arcuate and concentric 10 with said buffing surfaces, and a spreader having arcuate buffing and pulling surfaces slidably engaging the buffing and pulling surfaces, respectively, on the coupler and having the arcuate surfaces engaging arcuate surfaces on the 15 said portions, said spreader being provided with a spacer positioned within said slot having a horizontally disposed perforation therein. 3. In a railway car, a car coupler shank having a slot forming spaced apart portions in combination with a spreader pivotally connected thereto and provided with a spacer projecting into said slot having a horizontally disposed perforation therein to receive a connecting draft key and form a connection therewith under 20 buffering or pulling movement of the coupler. 4. In a railway car, a car coupler shank having a slot forming spaced apart portions in combination with a spreader having spaced apart horizontal flanges positioned respectively above 25 and below the shank and pivotally connected thereto, said spreader also provided with a spacer projecting into said slot having a horizontally disposed perforation therein to receive a connecting draft key and form a connection therewith under buffering or pulling movement of the coupler. 5. In a railway car, a car coupler shank having a slot forming spaced apart portions, a spreader pivotally connected thereto and projecting into said slot having a horizontally disposed perforation therein, a yoke with portions on each side of said coupler provided with perforations, and a key passing through the perforations in the yoke and the perforation in the 50 spreader to form a connection between the spreader and the yoke under buffering and pulling movements of the coupler. 6. In a railway car, a car coupler shank having a slot forming spaced apart portions, the 55 forward end of said slot forming a curved surface, in combination with a spreader pivotally connected thereto and provided with a spacer projecting into said slot having a horizontally disposed perforation therein to receive a connecting draft key to form a connection between the spreader and key under buffering or pulling movements of the coupler, the forward end of said spacer forming a curved surface concentric with and slidably engaging the curved surface of the slot in the coupler shank. 7. A swivel butt coupler involving a stem portion and a swivel block comprising alternately interspaced flanges intercalated with respect to each other, an intermediate flange on the swivel block extending forwardly of the remaining flanges thereof, the forward surface of said intermediate flange and the corresponding surface on the stem being normally in engagement and coaxially curved for transmitting buffering forces while permitting pivotal motion therebetween, and pivotal means extending between, connecting adjacent flanges on said stem and swivel block, and coaxial with said engaged surfaces, the intermediate flange on said swivel block being formed with a horizontally disposed slot for entirely surrounding an associated draft key. 8. In railway draft rigging, in combination with draft sills, a yoke, a coupler comprising a stem portion and a swivel block having alternately interspaced flanges intercalated with respect to each other, an intermediate flange on said swivel block extending forwardly of the remaining flanges thereof, the front surface of said intermediate flange and the co-operating surface on the stem being coaxially curved for permitting pivotal motion and normally in engagement for the transmission of buffering forces, pivotal means extending between adjacent flanges on said stem and swivel block for connecting said coupler and block, the intermediate flange on said swivel block being slotted, said slot extending forwardly of the pivotal means connecting the stem and block and discontinued rearwardly of the front edge of said flange, and a horizontal key received in said slot and corresponding slots in said yoke and with its ends received in corresponding slots in the sills, whereby it is adapted to function for the transmission of buffering forces which are delivered from the coupler stem to the swivel block and from there through the key to the sills. 105 110 115 120 125 130 135 140 145 150
- ARTHUR E. SMALL.
